RADIO CIRCUITS

Klaas Posthumus, Eindhoven, Netherlands, assignor to Radio Corporation of America, a corporation of Delaware

Application December 8, 1933, Serial No. 701,434
In Germany December 12, 1932

10 Claims.

The invention relates to installations for the selective reception of electrical high-frequency oscillations and may be applied to radio-receiving systems, amplifying systems, etc. In such an installation use is mostly made of one or more LC circuits. An increase of the selectivity is obtained in this case by increasing the number of LC circuits and by reducing as much as possible the damping in each circuit. The invention provides means which allow of obtaining a determined selectivity with less tuning means than have been necessary up to the present. These means consist in giving a single tuning circuit a periodic damping variation.

15 The increase of the selectivity which is thus produced may be explained as follows:

If in a tuned circuit the inductance, the capacity and the resistance are denoted by L , C and R_1 , respectively, and if a tension E is applied 20 to this circuit, the total current passing through said circuit is equal to

$$25 \quad \frac{E}{j\omega L - \frac{j}{\omega C} + R_1}$$

If now the resistance is varied from R_1 to R_2 the variation of the current intensity will be:

$$30 \quad \frac{E}{j\omega L - \frac{j}{\omega C} + R_1} - \frac{E}{j\omega L - \frac{j}{\omega C} + R_2} = \frac{E(R_1 - R_2)}{\left(j\omega L - \frac{j}{\omega C} + R_1\right)\left(j\omega L - \frac{j}{\omega C} + R_2\right)}$$

40 When now the resistance is periodically varied, for example with the aid of an ultra-audible frequency q , between the values R_1 and R_2 , when after rectification this frequency q is eliminated by means of a filter, it appears from the above 45 formula that the selectivity of this system, which comprises a single tuned circuit whose resistance fluctuates between two determined values, corresponds to the selectivity of a system having two tuned circuits.

50 In the foregoing calculation it was assumed that the value of the resistance varies abruptly from R_1 to R_2 and conversely. It is also possible, however, to obtain an increased selectivity by sinusoidally varying the value of the resistance.

(Cl. 250—20)

If q denotes the frequency of the variation of the damping and if

$$j\omega L - \frac{j}{\omega C} + R = p$$

the variation of the current intensity is

$$5 \quad \frac{1}{p + R_1 \sin qt} = \frac{1}{p} \left(1 - \frac{R_1}{p} \sin qt + \frac{R_1^2}{p^2} \sin 2qt \dots \right)$$

when $p \gg R_1 \sin qt$.

10 If now a filter is provided which is tuned to the frequency of the variation of the damping, the selectivity is determined by the term

$$15 \quad \frac{R_1}{2}$$

i. e. that the selectivity corresponds to that of two tuned circuits.

If the amplifier is tuned to the second or third harmonic, the selectivity corresponds to that of 20 three or four circuits.

In order to obtain the above mentioned effect it is however necessary that the variation of the resistance should be a purely sinusoidal one, at least that only very weak harmonics should be 25 produced.

This result may be obtained in practice by arranging in parallel with the tuned circuit the anode-cathode resistance of a tube whose input circuit has applied to it a voltage which varies 30 sinusoidally. This results in a sinusoidal variation of the slope of the tube, i. e. that the internal resistance of this tube varies inversely proportionally. As the above formulae apply for a resistance connected in series within the circuit 35 and a parallel resistance may be replaced by a series resistance of the value

$$40 \quad \frac{L}{CR}$$

the parallel-connection of a tube whose internal resistance varies in proportion to

$$45 \quad \frac{1}{\sin qt}$$

corresponds to a series-connection of a resistance whose value varies sinusoidally.

There is pointed out below a mathematical discussion of the advantages arising from providing a resonant circuit in the output circuit of the relay which is tuned to a multiple of the fundamental frequency of damping.

50 If an E. M. F. E is working in an oscillating cir-

55

cuit comprising a resistance R , a self inductance L and a capacity C , there will ensue a current

$$5 \quad I = \frac{E}{R + j\omega L + \frac{1}{j\omega C}}$$

If a variable resistance $R_1 (1 + \sin \omega t)$ is inserted in the oscillatory circuit the current I changes to:

$$10 \quad I' = \frac{E}{R + R_1 + j\omega L + \frac{1}{j\omega C} + R_1 \sin \omega t}$$

Now put:

$$15 \quad R + R_1 + j\omega L + \frac{1}{j\omega C} = p$$

We find then:

$$I' = \frac{E}{p + R_1 \sin \omega t} =$$

$$20 \quad E \left[\frac{1}{p} - \frac{R_1}{p^2} \sin \omega t + \frac{R_1^2}{p^3} \sin^2 \omega t - \frac{R_1^3}{p^4} \sin^3 \omega t + \dots \right]$$

Filtering out from this frequency spectrum the frequency $n\omega$, we get a voltage of which the amplitude is proportional to

$$\frac{1}{p^{n+1}}$$

To find the selectivity the amplitude of this voltage for the desired frequency ω_0 has to be compared to the amplitude for an undesired frequency ω_1 .

For $\omega = \omega_0$ we find $p_0 = R + R_1$

For $\omega = \omega_1$ we find

$$35 \quad p_1 = R + R_1 + j\omega_1 L + \frac{1}{j\omega_1 C}$$

The selectivity is therefore equal to:

$$40 \quad S_{nq} = \frac{(p_1)^{n+1}}{(p_0)^{n+1}} = \frac{\left| R + R_1 + j\omega_1 L + \frac{1}{j\omega_1 C} \right|^{n+1}}{(R + R_1)^{n+1}} = \frac{\left[1 + \left(\frac{\omega_1 L - \frac{1}{\omega_1 C}}{R + R_1} \right)^2 \right]^{\frac{n+1}{2}}}{1 + \left(\frac{\omega_1 L - \frac{1}{\omega_1 C}}{R + R_1} \right)^2}$$

45 For the selectivity without the use of the variable resistance we find:

$$50 \quad S_0 = \frac{(R + j\omega_1 L + \frac{1}{j\omega_1 C})}{R} = \sqrt{1 + \left(\frac{\omega_1 L - \frac{1}{\omega_1 C}}{R} \right)^2}$$

or:

$$\left(\omega_1 L - \frac{1}{\omega_1 C} \right)^2 = R^2 (S_0^2 - 1)$$

55 Substituting this last equation into the equation for S_{nq} we find:

$$S_{nq} = \left[1 + \frac{R^2}{(R + R_1)^2} (S_0^2 - 1) \right]^{\frac{n+1}{2}}$$

60 Now S_0 is always greater than one, so that the part between the square brackets is always greater than one. It will therefore always be possible by choosing a harmonic of sufficiently high order to obtain a selectivity greater than S_0 .

65 The increase of selectivity is greatest when R_1 is small with respect to R . For this case the above formula changes to: $S_{nq} = S_0^{n+1}$. It will be immediately clear that the selectivity in this case is greater, the higher the order of the harmonic, which is filtered out. The choice of a value of R_1 , which is small with respect to R involves the disadvantage that the output voltage is very small, as will easily be seen from the equation representing the development of the current I' in a series.

For large values of R_1 , i. e. for values of R_1 larger with respect to R , the above formula changes to:

$$S_{nq} = \left[1 + \frac{S_0^2 - 1}{R_1^2} \right]^{\frac{n+1}{2}}$$

from which it will be seen that a harmonic of comparatively high order has to be chosen in order to obtain an increased selectivity.

Any person skilled in the art will be able to choose appropriate values of R_1 and n for a desired object.

The choice of a multiple of the fundamental damping frequency is especially useful when the initial selectivity S_0 is small.

For instance for $S_0 = 1.5$ and $R = R_1$ we find:

$$S_q = 1.31; S_{2q} = 1.50; S_{3q} = 1.72$$

The third harmonic offers an increased selectivity, whereas the filtering out of the fundamental frequency would cause a decrease of the selectivity.

For $S_0 = 1.5$; $R_1 = \frac{1}{2}R$, we find:

$$S_q = 1.55; S_{2q} = 1.94; S_{3q} = 2.42$$

The use of the fundamental frequency in this case would not cause an appreciable increase of the selectivity, whereas the use of the second or third harmonic would yield a considerable improvement.

As to the validity of the above formulae it has to be remarked, that the components of frequency $n\omega$ contained in the terms of the series with exponents $3n\omega$, $5n\omega$, etc., have been neglected. This does not involve a qualitative error in the results however, as the coefficients of the higher order terms decrease rapidly with increasing values of the exponent for the frequency ω_1 and at a considerably slower rate for the frequency ω_0 . As the selectivity is formed by dividing the amplitude for the frequency ω_0 by the amplitude for the frequency ω_1 , the said components of frequency $n\omega$ can only bring about a further increase of the selectivity.

The invention will be explained more fully with reference to the accompanying drawing which represents by way of example two embodiments of the circuit arrangement according to the invention, whereof Fig. 1 shows the tuned circuit damping by a utilization of the internal resistance of a tube, and Fig. 2 shows therefor the use of a periodic alteration of a retroactive coupling.

The circuit arrangement shown in Figure 1 consists of a detector D_1 whose grid circuit comprises a circuit LC tuned to the frequency ω which is to be received. The damping of this circuit varies periodically as in parallel with the inductance or with part thereof is connected the internal resistance of a tube M . The resistance of this tube is sinusoidally varied with the aid of a generator g connected in the input circuit of said tube and producing oscillations of the ultra-audible frequency q , for example of 20,000 cycles. The detector D_1 is followed by a medium frequency amplifier which is tuned to a harmonic of the frequency of the generator g (nq). The low frequency demodulation is brought about with the aid of a second detector D_2 .

A variation of the resistance in the tuned circuit may be obtained not only as is shown in the form of construction above described, by parallel connection of the internal resistance of the amplifying tube, but also by periodically altering the retroactive coupling.

Such a circuit arrangement is shown in Figure 75

2. In the grid circuit of a detector D_1 is included a circuit which is tuned to the frequency ω to be received and which at the same time is located in the input circuit of an auxiliary tube M . This input circuit comprises in addition a generator g which produces an auxiliary frequency q . In the anode circuit of the tube M is connected a coil L_1 which is coupled with the circuit LC and which consequently causes the damping of this circuit to vary periodically, viz. at the frequency q .

10 The output circuit of the detector again comprises a filter tuned to the frequency q or to a harmonic of said frequency (nq).

15 The latter method in which the variation of the damping is obtained by periodically altering the retroactive coupling, affords relatively to the method in which the damping of the circuit is periodically increased, the advantage that thus the circuit is improved, that is to say that it obtains less damping whereas in the case of parallel 20 connection of a resistance the damping is increased.

I claim:

25 1. A relay circuit arrangement for the selective reception of electrical oscillations comprising a tuned input circuit for said relay, means for periodically varying the damping of said tuned circuit and a filter circuit for a multiple of the damping frequency connected in the output of the relay.

30 2. A circuit arrangement as claimed in the preceding claim in which the damping in the tuned circuit varies sinusoidally.

35 3. A relay circuit arrangement for the selective reception of electrical oscillations comprising a tuned input circuit for the relay, means for periodically varying the damping of said input circuit comprising a thermionic tube connected in parallel with the tuned input circuit, said tube being provided with means for varying its internal 40 resistance periodically, a filter circuit connected in the output circuit of the relay, said filter circuit being tuned to a multiple of the frequency of damping.

45 4. In a radio system a source of signal energy, an electronic tube provided with an input circuit and an output circuit, means for electrically connecting the source to the input circuit said input circuit being tunable to any frequency within a predetermined range of frequencies, 50 a variable resistance means shunted across at least a part of said input circuit, means for varying the value of said resistance at a predetermined rate to thereby periodically damp said input circuit, said output circuit including a tuned circuit tuned to a harmonic of the frequency of variation of said resistance and a utilizing circuit coupled to said output circuit.

55 5. In a circuit arrangement as claimed in the

next preceding claim wherein said variable resistance means comprises an electronic tube having its output circuit connected across the portion of the said tuned circuit and an input circuit including a periodically varying source 5 of energy.

6. The method of receiving signal modulated carrier energy which comprises impressing the modulated carrier upon a tuned circuit which is tuned to the frequency of the carrier and periodically varying the damping of the tuned circuit at a supersonic frequency which is different than the frequency of the carrier whereby there is introduced into the tuned circuit energy to compensate for the energy lost in the tuned circuit due to the inherent resistance of the tuned circuit, combining the two energies and utilizing, from the products of the combination, energy of a frequency which is a multiple of the supersonic frequency.

10 7. In apparatus for the selective reception of signal waves, a thermionic tube circuit including a tunable input circuit adapted to be tuned to the frequency of the desired signal waves and an output circuit, damping means for the tunable 15 input circuit including means for periodically varying the damping of said input circuit at a frequency which is low as compared to that of the signal waves, said output circuit including a resonant circuit tuned to an integral multiple 20 of said variation frequency and a utilizing circuit coupled to said output circuit.

8. An arrangement as described in the next preceding claim characterized by that the damping means comprises a thermionic tube having 25 an input circuit and an output circuit and coupling between said circuits.

30 9. An arrangement as described in claim 7 characterized by that the damping means comprises an auxiliary electronic tube having an input circuit and an output circuit which are coupled together, said input circuit including at least a portion of the tunable input circuit and by that the means for periodically varying the damping of the input circuit of the first tube 35 comprises an alternating current generator in the input circuit of the auxiliary tube.

40 10. In apparatus for the selective reception of signal waves, a detector circuit having a tunable input circuit adapted to be tuned to the frequency of the desired signal waves and an output circuit, means for variably damping said tunable input circuit at supersonic frequency which is different than the frequency of the signal waves, and a resonant circuit tuned to an integral 45 multiple of said variation frequency connected in the output circuit of said detector.

KLAAS POSTHUMUS.
